SLIDABLE FASTENER

Harry London, New York, N. Y.

Application February 7, 1938, Serial No. 189,219

1 Claim. (Cl. 24—207)

The present invention relates to a closure or fastening means and more particularly to a closure of the slidable type, having two parallel cord-like members secured together for approximately one-half their length.

One of the objects of the invention is the construction of a slidable fastener which finds a ready application for use in conjunction with pocket bags, cloth cosmetic receptacles, handkerchief bags, sewing bags and, in fact, in any and all places where an easily operable closure or fastening means is desired.

Still another aim of the invention is the formation of a slidable fastener characterized by simplicity of structural detail and which may be readily applied to the various articles aforementioned.

Yet a further aim of the invention is the construction of a slidable closure entirely devoid of mechanical metal fastening means and in which the slotted guides or keepers may be readily attached by means of stitching with thread or by an adhesive, or the like.

Other aims and objects will be apparent from the detailed description hereinafter appearing when taken in conjunction with the appended drawings forming a part hereof, to which reference is now made, and in which:

Fig. 1 is a top plan view of one form of the novel slidable closure or fastener shown as unattached and which may be sold or merchandized as such for subsequent sewing or attachment to a bag or the like.

Fig. 2 is a sectional view taken on line 2—2 of Fig. 1.

Fig. 3 is a side elevational view showing the slidable fastener or closure of Fig. 1 attached to a cloth cosmetic receptacle.

Fig. 4 is a sectional view taken on line 4—4 of Fig. 3.

Fig. 5 is an elevational view similar to that of Fig. 3 but showing a modified form of the slidable closure.

Fig. 6 is a detail view partly in section and partly broken away of the closure of Fig. 5, showing the manner of securing the slotted members or guides to the cloth receptacle.

Fig. 7 is a top plan view of one of the novel bead-like slotted members or guides of the closure of Fig. 5.

Fig. 8 is a sectional view taken on line 8—8 of Fig. 7.

Fig. 9 is an elevational view similar to that of Fig. 5, but showing still another modified form of the invention.

Fig. 10 is a sectional view taken on the line 10—10 of Fig. 9.

Referring first to Figs. 1 to 4 inclusive there is shown in Fig. 1 one form of the novel slidable closure generally designated as C. The closure comprises preferably a pair of parallel cord members 10—11 secured at their ends 13 and 14. It will be understood that the members 10 and 11 do not have to be made of yarn or the like and may also be constructed of wire or any other suitable material, preferably of a flexible character. The cord members 10 and 11 are secured intermediate their ends for approximately one-half their length, a length equal to the opening of a receptacle, by means of thread stitching 14. The other half of the cord members are unattached as indicated at 15 in Fig. 3 of the drawings. A plurality of cylindrically-shaped keepers or guides 16 are secured in spaced relationship to the edges of cloth strips 17—18. As indicated in Fig. 2 the strips are folded upon themselves and the guides 16 are secured within the folded portions of the strips 19—20 by means of an adhesive or the like. From the construction shown in Fig. 2 it will be appreciated that each of the bead-like guide members 16 is effectively covered by the folded portions 19—20 of the cloth members 17—18, so as not to be materially exposed to view. By reference to Figs. 2 and 4 it will further be seen that each of the bead-like guide members 16 is provided with a longitudinal slot 21. The cords 10 and 11 are slidable in the keepers and, when the cords are moved to the right as viewed in Fig. 1, the keepers 16 will be drawn toward each other with the stitching 14 passing through the slits 21 in said keepers. This forms an effective closure as will be understood, while the closure may be opened by movement of the cord members 10 and 11 to the left, as viewed in Figs. 1 and 3. Parallel lines of stitching 22—23 serve to keep the folded portions 19—20 of the cloth sections 17—18 together. The closure C may be attached to a cosmetic receptacle or bag 25 by means of stitching the cloth strips 17 and 18 to the folded edges 26 and 27 of the receptacle 25, the lines of parallel stitching being designated by the reference numerals 28 and 29.

Referring now to Figs. 5, 6, 7 and 8 of the drawings, there is shown a modified form of the invention, in which each of the cylindrically-shaped, bead-like members 36 is provided with a pair of spaced apertures 37—38 in the plane of the longitudinal slot 39 of the bead-like guide member 36. The members 36 are secured to the

- folded edge 40 of a receptacle 45 by means of stitching 41 passing through the spaced apertures 37 and 38, the stitching taking the form of a chain, as will be apparent from an inspection of Fig. 6 of the drawings. As will be seen each of the edges defining the opening in the closure member 25 is provided longitudinally thereof with guide members 36 so that when the cords 19 and 11 are moved to the right, as viewed in Fig. 5, the opening in the receptacle 45 will be closed by the stitching 14 and, when the cord members are moved to the left, the opening in the receptacle will be unfastened.
- The construction of Fig. 9 is similar to that of Fig. 5, only in this instance, the bead-like guides 36 are alternately arranged on the opposed edges of the receptacle 25, the members 36 being secured to the edge of one side wall 58 of the receptacle 45 while, on the other edge 51, the members 36 are secured slightly below the edge and inwardly toward the edge of the receptacle 45. The latter construction may be used on bags or other receptacles where a somewhat cheaper construction is not detrimental.
- From the above description it will be appreciated that there has been provided a slidable closure of great simplicity and which is yet very effective for the purpose contemplated. No metallic fastening means are employed, the bead-

like members being secured either directly to the receptacle or to cloth strips which may be sewed to the receptacle by means of either an adhesive or simple thread stitching. The bead-like guide members may be made of hard rubber, Celluloid, glass, Bakelite, or of any suitable material.

It will be apparent to those skilled in the art that various modifications may be made to fall within the spirit of the invention, and it is contemplated to cover all such and to be limited in this respect only as may be necessary by the scope of the claim hereto appended.

What I claim is:

A slidable fastener comprising opposed edges defining a closure opening, a plurality of spaced guides secured to each of said edges with the guides alternately arranged on said edges, each of said guides consisting of a hollow cylindrical member opened at opposed ends and having a longitudinal slot connecting said ends and each guide having an opening in the plane of said slot, the securing means for said guides comprising a chain of stitching extending through the openings in said guides and through said edges, a cord slidable in each set of the guides, said cords being stitched together for a portion of their length.

HARRY LONDON.
